METHOD AND APPARATUS FOR CLOSING
TUYERESMichael Ryan, Braddock, and Edwin T. Warren,
Munhall, Pa.

Application September 1, 1936, Serial No. 99,000

2 Claims. (Cl. 266—42)

The invention relates to blast furnace tuyères and particularly to a method and means for closing or sealing damaged tuyères to facilitate their replacement.

5 It is an object of this invention to provide a novel method and means for sealing tuyères which is easily, safely and rapidly performed by the ordinary workman with a minimum of inexpensive equipment.

10 The above and other objects will be apparent in referring to the following description and the accompanying drawing in which:

15 Figure 1 is an elevation, partly in section, of the apparatus employed in carrying out the method of the present invention.

Figure 2 is a section on line II—II of Figure 1.

Referring to the accompanying drawing, the numeral 2 indicates generally a wall of a blast furnace. The wall 2 has a tapered aperture 4 adapted to receive a hollow conical cooler 6 having a chamber 7 through which cooling fluid is circulated by any suitable means (not shown). A tuyère 8 having an aperture axially therethrough is tapered so that it fits in the nose of the cooler 6 and protrudes out into the blast furnace. In order to cool the tuyère 8, there is provided a chamber 9 through which a cooling fluid is circulated. A blow pipe 10, connected to the tuyère 8 by an air tight contact union, supplies the tuyère 8 with a blast of air received from a lower tuyère stock 12.

The lower tuyère stock 12 is suspended from an upper tuyère stock 14 by hanger bolts 16 and is prevented from swinging by a key 17 in the bolt

35 16. As shown in Figure 1, a bolt 18 bears upon a flange on the lower tuyère stock 12 and forces it against the blow-pipe 10 so that, the blow-pipe 10 is firmly held between the tuyère 8 and the lower tuyère-stock 12.

40 The lower tuyère-stock 12 has a peep hole 20 adapted to give a view through the blow-pipe 10 and the tuyère 8 into the blast furnace. The peep hole 20 has a cover 22 pivotally mounted on a bolt 24. The cover 22 is adapted to be locked in place over the peep hole 20 by a slotted bolt 26.

A clay gun 30 is provided to rapidly and safely close the axial aperture through the tuyère 8 and the cooler 6. The gun 30, which is positioned through the peep hole 20, extends to the tuyère 8 and is provided with a plunger 32 which is prevented from leaving the gun by a collar 33 at the nozzle of the gun. A handle 34 is connected to the gun 30 by rods 35 so that the gun 30 is easily supported and handled. To limit the inward movement of the gun and to position it as desired, a collar 36 is slidably mounted on the barrel of the gun 30 and secured in the desired position by a set screw 37. The collar 36, being of a larger

diameter than the peep hole 20, prevents the escape of hot gases around the gun 30.

The gun 30 is operated by air pressure supplied to it through pipe 38 and controlled by a valve 39. A pipe cap 40 connects the pipe 38 to the gun 30, so that by turning the valve 39 compressed air is admitted to the gun 30. When sufficient pressure is obtained in the gun 30, it forces the plunger 32 to move towards the nozzle of the gun 30 and thereby, continuously expel clay 42 from the gun 30. The clay 42, when expelled, accumulates in the tuyère 8 and the cooler 6, and closes the aperture therethrough.

By closing or sealing the tuyère in this manner, it is possible to remove the blow pipe 10 and the tuyère 8 without danger of injuring or burning the operators. In addition, the time required to remove a tuyère is considerably decreased over any methods of removing tuyères heretofore practiced. After pulling out the damaged tuyère 8 some of the clay 42 remains in the cooler 6 and prevents a severe outrush of gas and cinders from the furnace and, in addition, the men are far enough away from the furnace that they will not be burned. Then the opening through the cooler 6 is sealed in any desired manner such as by a re-application of the gun 30 and a new tuyère is forced into position through the clay in the cooler 6.

It will be appreciated that the scope of the invention is not restricted to the specific form illustrated and described, but is actually defined in the appended claims.

We claim:

1. The method of removing and replacing tuyères from blast furnaces which consists in continuously forcing clay into a tuyère and its accompanying cooler, so as to fill the tuyère, removing the blow pipe associated with the tuyère, removing the tuyère, forcing clay under pressure into the cooler from which the tuyère has been removed, until the cooler is closed, and then inserting a new tuyère thru the clay in said cooler.

2. Apparatus for sealing the opening through a tuyère in blast furnaces comprising a pipe of sufficient length to extend through the peep hole of a lower tuyère stock to a point adjacent said tuyère, a handle on said pipe on the portion remaining outside said stock, means adjustably mounted on said pipe and adapted to form a seal between said pipe and stock when said pipe extends into said stock, a piston in said pipe and means for operating said piston to discharge sealing clay contained in said pipe from its inner end and forcing said clay into said tuyère where by said opening through it is sealed.
